SLIDE FILE

Albert Edward Milliken, Kingston, N. Y.

Application September 20, 1951, Serial No. 247,481

2 Claims. (Cl. 312—310)

1

This invention relates to a file for picture slides. Heretofore picture slides have been kept in unclassified condition in envelopes or in bureau drawers where much time and effort is lost in locating the slides which are desired to be exhibited.

It is an object of the invention to provide a slide file presenting an attractive appearance and in which a large number of slides may be kept.

A further object of the invention is to provide a slide file having means for separating the slides into groups with identifying means for each of the groups.

An additional object is to provide a slide file having identifying means for each group of slides with detachable mounting means for the identifying means.

Other objects will appear hereinafter.

In the drawings:

Figure 1 is a side elevation of the slide with a portion shown in vertical section.

Figure 2 is a front elevation of the slide shown in Figure 1.

Figure 3 is a view similar to Figure 2 with the front cover removed.

Figure 4 is a fragmentary view partly in section showing the front cover on the casing.

Figure 5 is a longitudinal vertical section of one of the drawers, showing the slides and the adjustable identifying supports, and

Figure 6 is a perspective view of one of the adjustable supports.

Referring to the drawings, the letter A indicates the file as a whole. The file is provided with a removable front cover B, and a plurality of slidable drawers C, preferably arranged in vertical alignment as seen in Figure 3.

The case is provided with a top 1, bottom 2, open front 3, back 4 and sides 5 and 6. Case A, sides, and bottom are constructed of two layers of card-board 7, 8 as seen in Figure 3, except at the front thereof.

The front of the case has the outer layer 8 cut away to provide a projecting flange 9 which is frictionally engaged by the flange 10 of the front cover B. This cover has a front wall 11 to which is attached by adhesive wooden back 12 having a covering 13 of material such as leather or artificial leather so as to give to the structure the appearance of a book end.

The drawers C are each supported upon a series of horizontally arranged ledges 14 that are vertically spaced from each other a distance greater than the height of the drawer front portions 15 leaving a space 16 between these front

2

portions and the ledge 14 above the drawer. Each drawer is provided with a handle 17 whereby the drawer may be slid forward or rearward in the case, or entirely removed therefrom to obtain access to the contents of the drawers. The back portion 18 of each drawer is preferably of the same height as the front portion, and the sides may be of any suitable height to position the slides 19 and the follower plates 20. These plates are higher than the front portion 15 of the drawers in order that an identifying legend such as seen in Figure 6 may be readily observed.

Each of the follower plates 20 has a slot 21 located centrally and adjacent its lowermost end, and a shoe 22 which rests upon the bottom of the drawer and which assists in guiding the follower plate as it is slid forward or backward in its drawer.

A tape 23 of steel or other metal as seen in Figure 5 extends longitudinally of each drawer and is threadedly engaged in each slot 21 in order to guide the follower plates 20. The ends of the tape are suitably secured to the ends 15 and 18 of each drawer so that it lies flat in the bottom of the drawer.

It will be noted that all of the drawers are available for inspection upon removal of the cover B. Suitable legends may be inscribed or otherwise affixed to the front drawer portions 15 to designate the contents of each drawer. Additionally the follower plates may contain other identifying means as shown in Figure 6 to indicate the contents of the several slides 19 that are located between each pair of follower plates, or in front of a follower plate.

As an example, one of the drawer front portions 15 could have an inscription "South America" thereon, while the follower plates 20 of that drawer could contain identifying means for each plate such as "Brazil," "Argentina," "Chile," "Venezuela," etc. Similarly other plates could contain identifying means for South American cities, etc.

I claim:

1. A slide file comprising a casing, a plurality of vertically arranged drawers in said casing each including a drawer front portion, said front portion of each drawer being of a height less than the vertical distance between a pair of said drawers next to each other, and means for masking the front portions of each of said vertically arranged drawers, and the spaces between said drawers, said means comprising a removable cover extending from the top to the bottom of said casing, and means for detachably

attaching said removable cover to said casing, each drawer having a tape located in the lower portion thereof, a plurality of follower plates, and slots in said plates threadedly engaging said tape, said follower plates having upper portions extending above the front of said drawer, whereby insignia on said upper portions of said follower plates may be observed after the removal of said cover without opening said drawer.

2. A slide file comprising a casing, a plurality of vertically arranged drawers in said casing each including a drawer front portion, said front portion of each drawer being of a height less than the vertical distance between a pair of said drawers next to each other, and means for masking the front portions of each of said vertically arranged drawers, and the spaces between said drawers, said means comprising a removable cover extending from the top to the bottom of said casing, and means for detachably attaching said removable cover to said casing, said cover having a flange, said casing consisting of

a plurality of layers of material, one of said layers having a flange cooperating with the flange of said cover and a plurality of followers in each of said drawers, each follower plate having a slot, and a metal tape extending longitudinally of each drawer and threadedly engaging the slot of each follower plate.

ALBERT EDWARD MILLIKEN.
